RODERICK EDWARD BYRNE, OF OTTAWA, ONTARIO, CANADA, ASSIGNOR OF ONE-HALF
TO JOSEPH ROBERT CAMERON, OF OTTAWA, CANADA.

FIREPROOF SHUTTER.

991,605.

Specification of Letters Patent. Patented May 9, 1911.

Application filed March 26, 1910. Serial No. 551,771.

To all whom it may concern:

Be it known that I, RODERICK EDWARD BYRNE, of the city of Ottawa, in the Province of Ontario, Canada, have invented certain new and useful Improvements in Fire-proof Shutters, of which the following is a specification.

My invention relates to improvements in fire proof shutters, and the objects of my invention are to provide an improved form 10 of shutter having increased insulating properties, and also to provide an improved automatic means for closing the same in the case of fire.

15 The improved insulating effect is secured by forming the shutter of tubular air containing members, and the shutter is adapted to be automatically moved to closed position in case of a fire by means of a weight held 20 by a fusible link adapted to fall a determined distance, and in falling to engage and strike hooks on the shutter which cause the same to move to closed position, all as hereinafter more fully set forth and described in 25 detail in the accompanying specifications and drawings.

In the drawings: Figure 1 is a perspective view of the shutter. Fig. 2 is a perspective detail of a portion of the shutter. Fig. 30 3 is a side view of the reel on which the shutter is supported. Fig. 4 is a cross section through the reel on the line 2—2, Fig. 3. Fig. 5 is a sectional view through an alternative form of the invention.

35 In the drawings, like characters of reference indicate corresponding parts in each figure.

Referring to the drawings, A represents a window frame of usual construction and B 40 a reel supported in a casing C above the window frame, the reel being suitably journaled in side members 10 and 11 on the casing.

The reel itself is formed of a hollow tubular member having reduced ends 12 and 13 45 which are journaled in the side members as specified, the reel being thus hollow and filled with air is well adapted to resist the heat.

D represents the shutter proper, which is 50 in the form of a curtain composed of a plurality of transversely extending tubular members 14 through which flexible connecting means such as cables 15 extend, said cables being secured to the reel B, as by 55 clamping bolts 16 extending transversely

through the reel and having hook-shaped ends 17 to engage and clamp the cable.

The tubular members 14 may be conveniently formed of sheet metal and may if desired be each formed with a flange 18 60 adapted to overlap the adjacent member and, thereby, secure a very tight and completely closed shutter. As these members contain air, they are well adapted to resist the heat of the fire.

65 In order to permit the escape of the air when heated in the tubular member, the frame is provided with a plurality of ventilating apertures 30 extending over the edge of the guideway for the tubular members, 70 with which the ends of the tubular members communicate.

The ends of the tubular members slide in guideways 19 at the side of the window frame, said guideways as well as the casing 75 C, being of course, formed of fire proof material such as sheet metal.

In order to enable the shutter to be raised and lowered conveniently, it is counter-balanced by suitable means. In the embodiment illustrated, a conoidal drum 20 is provided at one end of the reel having a spiral groove into which a chain 22 fits having at 80 its extremity a weight 23 of sufficient amount to just counter-balance the shutter. An auxiliary balancing device (see dotted lines Fig. 1) is also provided consisting of a chain 24 and weight 25. The chain 24 is connected to the drum 20 at 26 and extends to the interior of the building, so that when it is desired to lower the shutter, the weight 25 on 85 the interior will be raised, permitting the shutter to overbalance and close.

In order to quickly move the shutter to closed position, in the case of fire, a weight 90 member 24 is provided, normally held at the top of the window by means which are destructible by heat such as a fusible link member 25, said weight being adapted when released to drop and engage suitable engaging 95 means on the shutter and, thereby, force the same to closed position. In the embodiment illustrated, these engaging means are in the form of hooks 26.

100 It is not necessary that the weight should fall the entire length of the window as the impact given by falling a short distance would impart sufficient velocity to the curtain to cause it to move to closed position. It is, therefore, desirable to limit the down- 110

ward movement of the weight when released, and this is done by chains 27 at opposite ends.

In the alternative form shown in Fig. 5, 5 the tubular members 14^a have the flanges omitted and are substantially circular in cross-section.

It will thus be seen that I have provided a simple and effective form of shutter which 10 is well adapted to resist fire, and which in the case of a fire will be automatically moved to closed position and at the same time the shutter is counter-balanced and may be closed at night or other periods without interfering with the automatic arrangement. 15

As many changes could be made in the above construction, and many apparently widely different embodiments of my invention within the scope of the claims could be 20 made without departing from the spirit or scope thereof, it is intended that all matter contained in the accompanying specifications and claims shall be interpreted as illustrative and not in a limiting sense.

25 What I claim as my invention is:

1. A fire proof shutter comprising a reel formed with a hollow tubular central portion and reduced ends, a casing inclosing said reel and journaling said ends, a drum 30 connected to said reel formed with a spiral

groove, a chain in said groove and a counter-balancing weight on the chain.

2. A fire proof shutter comprising a frame, a plurality of tubular air containing members, and means connecting said members, said frame being formed with 35 ventilating apertures permitting the escape of heated air from said tubular members.

3. A fire proof shutter comprising a frame formed with guideways therein and 40 ventilating apertures communicating with the guideways, and a plurality of tubular air containing members in the guideways.

4. A fire proof shutter comprising a reel, a casing inclosing said shutter and secured 45 on the exterior of a building, counter-balancing means connected to said reel and being accessible from the exterior of said building, auxiliary balancing means connected to said reel and accessible from the interior of said 50 building, and a fire proof curtain mounted on said reel formed with hollow, tubular air containing members.

In witness whereof I have hereunto set my hand in the presence of two witnesses.

RODERICK EDWARD BYRNE.
